UNITED STATES PATENT OFFICE.

GEORGE E. PRENTICE, OF BERLIN, CONNECTICUT.

FASTENER COMBINATION.

Application filed March 26, 1925. Serial No. 18,437.

To all whom it may concern:

Be it known that I, GEORGE E. PRENTICE, a citizen of the United States, residing at Berlin, in the county of Hartford and State of Connecticut, have invented certain new and useful Improvements in Fastener Combinations, of which the following is a specification.

My invention relates to improvements in fastener combinations, having to do with interlocking fastener construction as shown in my application that was filed April 28, 1924, Serial No. 709,643, and the object of my improvement is to provide stop means for limiting the closing movement of the slide in the form of a unitary piece that serves by its lateral ends to connect the individual spring members to the fabric and that has the intermediate portion of appreciable length so as to provide for a permanent and positive lateral spacing of the adjacent portions of said spring members.

In the accompanying drawing:

Figure 1 is a plan view of a set of fastener devices mounted on the two sides of a gap in fabric or the like, a slide for operating the same, a stop device at the fixedly closed end, and a bridging stop device embodying my invention at the other end.

Figure 2 is a side elevation of the slide and bridging device.

Figure 3 is a plan view of the blank for the bridging device.

Figure 4 is a sectional view on the line 4-4 of Fig. 1 showing the bridging device and the adjacent portion of the slide in the engaging position with said bridging device, other parts of the slide being shown in side elevation.

Figure 5 is a rear elevation of the bridging device.

My improved fastener combination comprises a set of fastener devices that consist of a series of left hand active locking members 10 on the left side of a gap 11 between the opposed edges 12 of a pair of strips 13 or the like of fabric and a series of right hand active locking members 14 on the right side of said gap 11 and which locking members are in the case of each series integrally connected and parts of a coil spring structure. That is to say, the left hand active locking members 10 are parts of the left spring 15 and the members 14 are parts of the spring 16.

At the rear ends the springs 15 and 16 are

fixedly interlocked and held together as well as secured to the fabric by means of a clip 17 that has suitable prongs for penetrating the fabric and being bent over to effect the necessary holding, said clip 17 serving as a stop for limiting the inward movement of the slide 18 in substantially the usual manner.

Said slide 18 is made of sheet metal and comprises a top plate 19, a bottom plate 20, with a space 21 between said plates for admitting the springs 15 and 16 and an integral connecting neck 22 of return bend form for interconnecting said plates 19 and 20. The top plate 19 has pendent flanges 23 at the lateral edges for guiding the springs 15 and 16.

The slide 18 has at the lower or rear end a mouth or opening 25 between the plates 19 and 20 that is an operative fit for the two springs 15 and 16 in interlocked position.

At the upper or forward end of the slide 18 the springs 15 and 16 make their exit in divergent relation through individual spaced outlets 26. Upper guide walls 27 are provided by swaging the material at the junctions of the top plate 19 and bottom plate 20 respectively with the structure of the neck 22, the two arms of the neck being pressed substantially together, said guide walls 27 converging inwardly and downwardly or rearwardly, and meeting in substantially V-formation.

Adjacent the apex 28 of said V-formation the arms 29 of the neck 22 are perforated to admit a rivet structure 30, substantially as in the application above referred to. In the present instance and corresponding to one form of structure that is shown and described in said application, said rivet structure 30 constitutes the forward end portion of a loop structure 31 that serves as a slide-mounting for a finger piece or handle 32 that has a perforation 33 for receiving said loop structure 31. Said loop structure 31 extends over the top plate 19, in spaced relation thereto, and the rear end thereof is in the form of a return bend structure 34 that is integrally connected to the rear edge portion 35 of the top plate 19.

Beyond the rivet 30 the arms 29 are connected by the diminutive yoke 36 and the structure of said yoke 36 and the adjacent portions of said arms 29 constitute a nose 37 that projects forwardly from the general structure of the slide 18. With the parts in

the fully locked position said nose 37 is housed within a cavity 38 that is provided in the part 39 that may be briefly referred to as the forward stop.

5 Said cavity 38 is at or adjacent the middle portion of the forward stop 39 and the lateral ends 40 are used as the securing means for holding the springs 15 and 16 in place, said springs being housed within 10 lateral extensions of the cavity 38, the walls being compressed against the springs.

Said walls comprise the top wall 41 and the bottom wall 42, these being parts of a sheet metal piece, a yoke 43 serving to interconnect said walls 41 and 42.

13 The yoke 43 is narrower than the walls 41 and 42 so as to provide clearance for the material of the strips 13 and to permit the same to extend beyond the structure of the 20 forward stop 39.

20 The nose 37, as described, will be positioned between the forward ends 44 of the springs 15 and 16 with the parts in the fully locked position, and, accordingly, when the 25 slide 18 is withdrawn from such position the

said forward ends 44 will be permanently and positively separated laterally one from the other. That is to say, the gap 11 will be of appreciable width, and will be bridged at the end by the structure of the forward 30 stop.

I claim as my invention:—

1. In combination, interlocking fastener devices arranged along the opposed edges of material bordering a gap, a slide for operating said devices and mounted for longitudinal movement thereon, said slide having at one end a pair of outlets, spaced laterally one from the other, and serving individually as exits for the fastener devices on the two 40 sides, the end of the gap that is opposed to said one end of the slide being bridged by a stop device, and said stop device cooperating with the slide to limit the movement thereof.

2. In a combination as described in claim 1, the part of said slide intermediate said exits making contact with said stop device in limiting such movement.

GEORGE E. PRENTICE.
